UNITED STATES PATENT OFFICE.

LEONARD D. PARKS, OF GATESVILLE, TEXAS, ASSIGNOR OF ONE-HALF TO
JOHN T. POST, OF GATESVILLE, TEXAS.

WINDOW-FASTENER.

SPECIFICATION forming part of Letters Patent No. 708,067, dated September 2, 1902.

Application filed May 15, 1902. Serial No. 107,488. (No model.)

To all whom it may concern:

Be it known that I, LEONARD D. PARKS, a citizen of the United States, residing at Gatesville, in the county of Coryell and State of Texas, have invented certain new and useful Improvements in Window-Fasteners; and I do hereby declare the following to be a full, clear, and exact description of the invention, such as will enable others skilled in the art to 10 to which it appertains to make and use the same.

This invention relates to window-fasteners, the object in view being to provide a combined automatic window fastener and lock by means of which a sliding window-sash may 15 be securely held and fastened at any desired point of elevation and locked against movement in either direction.

The combined fastener and lock hereinafter described combines simplicity and reliability 20 in operation and economy in the cost of manufacture.

With the above and other objects in view, the nature of which will more fully appear as the description proceeds, the invention consists 25 in the novel construction, combination, and arrangement of parts, as hereinafter fully described, illustrated, and claimed.

In the accompanying drawings, Figure 1 is a view in elevation of a portion of a window 30 sash and frame, showing a combined fastener and lock applied to the sash, with the casing of the fastener partly broken away to show the operation thereof. Fig. 2 is an enlarged sectional elevation of the fastener, showing 35 the parts in their operative positions. Fig. 3 is a view in elevation of a portion of a window sash and frame, showing a combined fastener and lock of modified form applied to the sash, with the casing of the fastener 40 partly broken away to show the operation thereof. Fig. 4 is an enlarged sectional elevation of said fastener, showing the parts in their inoperative position. Fig. 5 is a similar view showing the position the parts assume 45 when the sash is fastened. Fig. 6 is a similar view of another form of fastener.

Like reference-numerals designate corresponding parts in all figures of the drawings.

The combined window fastener and lock 50 contemplated in this invention may be applied either to a sliding window-sash, as

shown in Fig. 1, or to the window-casing, so as to bear against the sash. By reference to Figs. 2 and 3 it will be seen that the device comprises, essentially, a casing 1, consisting 55 of a rectangular frame elongated vertically to receive the operative parts of the fastener and lock and covered at one side by a plate 2, which, for the purpose of illustration, is broken away to show the interior mechanism. 60 The casing is further provided at opposite ends with attaching-ears 3, by means of which the device may be secured to the window sash or frame.

Within the casing are mounted two cams 65 4 and 5, the lower cam being provided with an operating-handle 6 of suitable length, projecting outward from the casing and having its movement in an upward direction limited by a stop-shoulder 18, formed on the casing. 70 The cams 4 and 5 are fulcrumed within the casing at the point 8, and one or both of the cams may be provided with a flat surface 9, to give the proper clearance for enabling the shaft to be raised and lowered without the 75 liability of the cams binding against the window-frame. The lower cam is provided with a pin or stud 10, against which bears the free and inclined end of a spring 12, which is coiled at 13 around a post or arbor 14 and extended therefrom to form an arm 15, which is held between the casing and a lug or shoulder 16. When the cams are in their inoperative 80 positions, the pin or stud 10 lies above the plane of the fulcrum 8, so that the pressure 85 of the spring 12 operates to hold the cam in its inoperative position, as shown in Fig. 1. The upper cam 4 is provided with a large notch or cut-away portion 4^a, thereby forming a shoulder 4^b, which is adapted to abut 90 against a corresponding shoulder 4^c, forming a part of the casing, said shoulders serving to limit the movement of the cam 4 in one direction. By cutting away a portion of the upper cam, as shown, the latter is made lighter 95 at one side of the fulcrum 8 than at the other, so that there is always a tendency for the heavier portion of the cam to move downward and outward, which has the effect of bringing said cam into engagement with the 100 window-frame. The upper cam is, however, normally held out of engagement with the

window frame or casing by means of the lower cam 5, which is itself held normally away from the window-frame by the action of the spring 12. As the circumferences or edges 5 of the cams are eccentric to their fulcrums, they coöperate in such manner that when the handle 6 is depressed the upper cam is allowed to gravitate into engagement with the window frame or casing, and when said handle 10 is elevated the lower cam operates against the upper cam, so as to restore the latter to its inoperative position. It will thus be seen that but a single handle 6 is necessary to operate both cams, and when the cams are 15 thrown into action they lock the window against both upward and downward movement.

In Figs. 3, 4, and 5 a slightly-modified form of window-sash fastener and lock is shown, the 20 upper cam 4 being provided with a handle 7, similar to but preferably shorter than the handle 6 on the lower cam. Both of the cams are provided with pins or studs 10, against which presses the convex surface of the free 25 end of the spring 12, the spring thus acting simultaneously on both cams. The cams are also provided with flat meeting or abutting surfaces 17, which come together when the cams are in their inoperative position and 30 act as stop-surfaces for limiting the movement of the cams toward each other, arresting their movement at a time when the surfaces 9 are parallel with the window frame or casing.

It will be noted that the pins or studs 10 35 are arranged nearer to the stop-surfaces 17 than the fulcrums or pivots 8, so that when the cams are in the position shown in Fig. 4 the pressure of the spring 12 against the studs 10 serves to hold the cams inoperative. On 40 the other hand, when the handles of the cams are moved away from each other the studs 10 pass above and below the pivots 8, whereupon the spring 12 acts to hold the cams in their operative positions and in engagement with 45 the window-frame. Accidental movement of the cams is thus prevented and the device as a whole rendered more reliable in action.

In Fig. 6 I have illustrated a simplified form of fastener in which but a single cam 19 is employed, the same being pivoted or fulcrumed at 20 and having a spring 21, which is given a sharp bend at the point 22, directly opposite and in line with the pivot 20, so that when the handle 23 of the cam is moved up or down the inclined portions of the spring at 55 opposite sides of the bend 22 will serve to hold the cam in the position to which it has been turned. In one position the cam will lock the window-sash against upward movement, and in the other position it will lock the 60 window-sash against downward movement. Under both constructions the spring acts to hold the cam or cams in operative engagement with the window frame or sash, as the case may be. 55

Having thus described the invention, what I claim is—

1. A combined window fastener and lock, comprising a casing, a pair of cams pivotally mounted therein and provided with eccentric 70 and coöperating meeting surfaces, an operating-handle, and a pin or stud on one cam, and a spring having its free end bearing against said pin or stud and adapted thereby to hold the cams either in their operative or inoperative 75 positions, substantially as described.

2. A combined window-sash fastener and lock, comprising a casing, a pair of cams fulcrumed therein and provided with eccentric and coöperating meeting surfaces, and operating-handle, and a pin or stud on one cam, a spring bearing against said pin or stud and adapted to hold the cam either in its operative or inoperative position, and a stop-shoulder on the casing, one of the cams being cut 85 away to form a coöperating stop-shoulder and to give the cam a preponderance of weight upon one side of its fulcrum.

In testimony whereof I affix my signature in presence of two witnesses.

LEONARD D. PARKS. [L. S.]
